H. IPSEN

RAZOR STROPPER

Filed Sept. 8, 1920

UNITED STATES PATENT OFFICE.

HENRIK IPSEN, OF BROOKLYN, NEW YORK, ASSIGNOR TO MAURICE L. BRANDT, OF NEW YORK, N. Y.

RAZOR STROPPE.

Application filed September 8, 1920. Serial No. 408,848.

To all whom it may concern:

Be it known that I, HENRIK IPSEN, a citizen of the United States, and a resident of the borough of Brooklyn, county of Kings, city and State of New York, have invented a certain new and useful Razor Stroppe, of which the following is a specification.

My invention relates to razor stroppe of the swing strap variety, in which a razor or 10 razor blade is suspended in the bight of a strop and the opposite sides of the blade are alternately presented to the surface of the strop as the latter is moved in opposite directions relatively to the blade, and at the 15 same time the blade is moved transversely relatively to the strop whereby the proper stropping and setting movements of the blade relatively to the strop are attained.

In the prior devices of this character, the 20 movement of the blade transversely of the strop has been accomplished by means of a screw which is rotated by pulling first on one end of the strop and then on the other, the screw being located in the bight of the 25 strop and being rotated by the engagement of the strap in the same manner that a pulley is rotated by a belt.

The object of the present invention is to 30 provide a device in which a razor blade or the like edged tool may be so positioned, arranged and manipulated that when each side 35 of the blade is presented to the strop there will be relative movement between the blade and the strop in which the blade will be caused to travel in the direction, transverse to the longitudinal axis, of the strop while the strop is being moved in the direction of its longitudinal axis, and wherein the blade will be caused to partake of rapid movements transversely of the strop whereby it, 40 the blade, will be drawn latterly across the path of movement of the strop a plurality of times during each full movement of the strop.

A further object is to provide simple, cheap and efficient means whereby opposite sides of the blades will be presented to the strop as the direction of movement of the same is changed, and whereby danger of cutting or otherwise marring of the strop is avoided.

These and further objects will more fully appear in the following specification and accompanying drawings considered together or separately.

I have illustrated one embodiment of my invention in the accompanying drawings, in which like parts in all of the several figures are designated by corresponding characters of reference, and in which

Fig. 1 is a longitudinal section of the device, partly in side elevation, the section being taken on the line 1—1 of Fig. 2.

Fig. 2 is a transverse section taken on the line 2—2 of Fig. 1.

Fig. 3 is an elevation of the drive roller.

Fig. 4 is an elevation of the same taken at right angles to Fig. 3.

Fig. 5 is a view similar to Fig. 2 but taken on a line just inside of the right hand side member 1 of Fig. 1, and

Fig. 6 is a diagrammatic view showing the path of movement of the blade in relation of the strop.

In carrying out my invention I provide a frame comprising side members 1, 1, preferably of key-hole shape as shown. The members are secured together in spaced relation by means of a cap piece 2 having a loop 3 through which is passed a strap 3^a whereby the frame may be secured to a stationary object, such as a hook, as is common.

Extending longitudinally of the frame and in proximity to the cap 2 is a stay 4 which is preferably riveted or otherwise secured to the side members and extending between them, and rotatably mounted on the stay 4 is roller 5. The side members are held in spaced relation by other stay members 6, 7, 8, 9, 10 and 11 as shown.

A strop 12 having a handle 13 at each extremity is placed within the frame between the roller 5 and the cap piece 2, there being a bight in the strop within which the roller 5 rests to be engaged by the strop which will act as a belt to rotate the roller in opposite direction as one end or the other of the strop is withdrawn from the roller.

Loosely carried on the stay rod 6 is a sleeve 14 to which is secured a blade holder comprising a pair of leaves 15 between which a razor blade is adapted to be secured in any desired manner, and with the edge of the blade projecting beyond the leaves in the direction away from the stay rod 6.

Rigidly secured to the sleeve 14 is a finger 16 which projects from the sleeve in the direction opposite the leaves 15. The free extremity of the finger is provided with a head 17 adapted to engage an endless, symmetrical

cam groove 18 in the cylindrical surface of the roller 5.

Loosely mounted on the stay rod 4 is a frame comprising a pair of oppositely disposed discs 19, 19, one at each end of the roller. The discs are connected by a bar 20 which is positioned between the roller and the stay 6. The bar is provided with a longitudinal slot 21 through which the finger 16 projects.

Rigidly secured to each disc 19 is a spring member 22. Each spring member comprises two legs which are crossed and engage opposite sides of the stay rod 6, whereby the bar 20 is normally positioned between the rods 4 and 6 with the finger 16 and the blade holder in the central position as shown in full lines in Fig. 2.

The strop, as shown in Fig. 2, is guided by the stays 7 and 9 on one side and by the stays 8 and 10 upon the opposite side of the frame. The stays 7 and 8 are so positioned relatively to the blade holder that when the latter is oscillated to engage the blade with the strop that portion of the strop in engagement with the blade will be backed up by a stay and there will be no danger of the strop being kinked, crimped or cut by the pressure of the blade, and rounding of the edge of the blade will be avoided.

The operation is as follows:

A razor blade is inserted in the blade holder from one end thereof with the edge of the blade projecting from the holder, and with the latter in the central position as shown in Fig. 2, the side members 1, 1 being cut away as shown to permit of the insertion and removal of the blade, and also to permit of endwise movement of holder.

The loop of the strop 3^a is placed over a hook or other stationary object, and the handles 13 are grasped one in each hand to bring the axis of the roller 4 in approximately the vertical position. The strop is now drawn back and forth over the roller whereby the latter is rotated first in one direction and then in the other as the right or left hand of the operator is drawn toward his body.

The initial movement of the roller will, by reason of the frictional engagement of the head 17 with the groove 18, swing the finger 16, and move the bar 20 in the direction of rotation, and the engagement of the finger 16 in the slot 21 of the bar will swing the blade holder in the opposite direction. This movement will bring one edge of the blade into contact with that portion of the strop which is moving toward the operator and the strop will be drawn along the blade in the direction from the back to the edge thereof. In swinging the discs 19 with the roller one leg of each spring 22 will be put under tension, and the tension of the springs together with the frictional engagement between the roller

and the strop will overcome the frictional engagement of the head with the side wall of the groove 18 and the movement of the discs will be arrested while the roller will rotate under the influences of the moving strop, with the edge of the blade in contact with that end of the strop moving toward the operator.

When the movement of one end of the strop toward the operator has reached its limit the handle on the other end thereof has been drawn almost into the frame. The motion is now reversed.

As soon as the first movement of the strop has ceased and before the reverse movement can start due to the pull on the now short end of the strop, the springs 22, 22 will release the edge of the blade from contact with the now long side of the strop and, the roller being at rest, the tension of the springs will release the head 17 from its engagement with the side wall of the groove and swing the blade holder to the central or neutral position. It will be seen that the head 17 is less in diameter than the width of the groove 18 and the arm being centered, as shown in Fig. 1 and in full lines in Fig. 2 the head will not engage the side wall of the groove until the roller has been given a partial rotation. When the rotary movement of the roller is arrested the springs will move the arm back to the position shown in full lines in Fig. 2 as such movement will be in the direction away from the inclined side wall of the groove.

When the short end of the strop is pulled the roller will be rotated in the opposite direction and the above described operation will be repeated except that the other side of the blade is presented to the stropping surface.

During the operation above described the engagement of the finger 16, with the cam groove 18 of the roller 5 will cause the blade holder to be reciprocated back and forth along the stay 6 and across the line of movement of the strop. The throw of the holder in the direction longitudinally thereof, and transversely of the line of movement of the strop will be limited only by the length of the slot longitudinally of the roller.

The holder will be reciprocated once for every rotation of the roller and the diameter of the roller will determine the number of reciprocations of the blade holder for each complete movement of the strop. In the embodiment of the invention illustrated, when the strop is pulled by the right hand of the operator, the roller, which is of comparatively large diameter, will make three revolutions and the blade will be reciprocated three times across the path of movement of the strop while one side thereof is in engagement with the strop.

When the left hand is pulled toward the

operator the blade will be swung over, its opposite side will engage that portion of the strop on the other side of the roller and the blade will be reciprocated three times 5 while that end of the strop is being pulled.

By making the roller smaller in diameter the number of reciprocations of the blade per movement of the strop may be increased to any desired extent.

- 10 The position of the pivotal point, on which the blade oscillates, relatively to the stays 7 and 8 being such that the edges of the blade engage the strop opposite those members provides a firm foundation for the 15 bearing points of the blade, and the pressure of the blade against the strop cannot bulge the latter outward to form a more or less deep pocket in which the edge of the blade may rest during the actual stropping. 20 The formation of such a pocket would cause the delicate edge of the blade to bear on a concave surface and said edge would become rounded as is frequently the case when an unskilled person attempts to strop a razor 25 on an ordinary swing strop and allows the strop to sag.

In addition with such a pocket there will be danger of the blade catching in the concaved surface of the strop before the blade 30 can swing free of the strop when the movement of the latter is reversed, thereby cutting or otherwise marring the stropping surface in addition to dulling the blade.

In accordance with the provisions of the 35 patent statutes, the principle of the invention has been described, together with the process which is now considered to represent the best embodiment thereof, but it is to be understood that the process described 40 is merely illustrative, and that the invention may be carried out in other ways.

Having now described the invention, what is claimed and desired to be secured by Letters Patent is:—

- 45 1. A device of the character described, comprising a strop, said strop being formed into a bight, a roller within the bight and adapted to be rotated in opposite directions by reciprocating movements of the strop, 50 there being an endless peripheral groove in the cylindrical surface of the roller, a support for the roller, a blade holder pivoted in the support and adapted to oscillate transversely of the axial line of the roller 55 and to be moved longitudinally of the roller, and a finger engaging a side wall of the groove and adapted to oscillate the holder, a spring for moving the holder to a position intermediate the extremes of oscillation, the engagement of the finger in the cam groove during rotation of the roller causing the holder to reciprocate in the direction at right angles to the direction of the oscillating movement.

65 2. A device of the character described,

comprising a strop, said strop being formed into a bight, a roller within the bight and adapted to be rotated in opposite directions by reciprocating movements of the strop, there being an endless peripheral groove in the cylindrical surface of the roller, a support for the roller, a blade holder pivoted in the support and adapted to oscillate transversely of the axial line of the roller and to be moved longitudinally of the roller, 70 and a finger carried by the holder and engaging a side wall of the groove and adapted to oscillate the holder, a pivoted element extending lengthwise of the roller and between the same and the holder, said finger engaging the element, and a spring carried by each end of the element for moving the holder to a position intermediate the extremes of oscillation, the engagement of the finger in the cam groove during rotation of the roller causing the holder to reciprocate in the direction at right angles to the direction of the oscillating movement.

3. A device of the character described, comprising a support, a roller rotatably mounted in the support, a strop, said strop being formed to a bight the roller being in the bight, and adapted to be rotated in opposite directions by reciprocating movements of the strop, an element pivoted in the axial line of the roller, a spring secured at its center to the element and having its ends engaging opposite sides of a stationary portion of the support, said element being capable of movement independently of the roller, there being an endless peripheral groove in the cylindrical surface of the roller, a blade holder pivoted in the support in parallel relation to the roller, a finger carried by the holder and adapted to engage the groove in the roller whereby the holder may be given a complete reciprocation in the direction axially of the roller on each revolution of the roller, said finger having a sliding engagement with the element, there being frictional engagement between the element and roller whereby the element will be oscillated as the roller is rotated in each direction, the spring tending to maintain the finger in the central position relatively to the extremes of oscillations of the element.

4. A device of the character described, comprising a support, a roller rotatably mounted in the support, a strop, said strop being formed to a bight, the roller being in the bight and adapted to be rotated in opposite directions by reciprocating movements of the strop, an element pivoted in the axial line of the roller, a spring secured at its center to the element and having its ends engaging a stationary portion of the support, said element being capable of moving relatively to the roller, there being an endless peripheral groove in the cylindrical sur-

- face of the roller, a blade holder pivoted in the support in parallel relation to the roller, a finger carried by the holder and adapted to engage the groove in the roller whereby
5 the holder may be given a complete reciprocation in the direction axially of the roller on each revolution of the roller, there being a slot in the element, said finger passing through the slot and having a sliding engagement with the element, there being frictional engagement between the element and roller whereby the element will be oscillated as the roller is rotated in each direction, the spring tending to maintain the finger in
10 the central position relatively to the extremes of oscillations of the roller.
15 5. A device of the character described, comprising a support, a roller rotatably mounted in the support, a strop passing over

the roller whereby the latter may be rotated, an element comprising an arm in frictional engagement with each end of the roller, said arms being connected by a bar, there being a slot in the bar, there being an endless peripheral groove in the cylindrical surface 25 of the roller, a stay member extending across the support and parallel to the axis of the roller, a blade holder loosely carried on the stay member, a finger carried by the holder, said finger passing through the slot 30 in the bar and the end thereof engaging the groove in the roller, a double acting spring carried by each arm of the element and adapted to bear against opposite sides of a member stationary relatively to the support. 35

This specification signed this 2nd day of September, 1920.

HENRIK IPSEN.
